UNITED STATES PATENT OFFICE.

ANDREW BYE, OF BUTTE, MONTANA.

HINGE FOR CASEMENT-WINDOWS.

1,268,678.

Specification of Letters Patent.

Patented June 4, 1918.

Application filed November 1, 1917. Serial No. 199,707.

To all whom it may concern:

Be it known that I, ANDREW BYE, a citizen of the United States, residing at Butte, in the county of Silver Bow and State of Montana, have invented certain new and useful Improvements in Hinges for Casement-Windows; and I do declare the following to be a full, clear, and exact description of the invention, such as will enable others skilled in the art to which it appertains to make and use the same.

My invention relates to improvements in hinges for casement windows and has for its object to provide a simply constructed and inexpensive, yet a highly efficient and durable hinge which will permit the sash to be turned completely around so that its outer side may be cleaned from the interior of the building, provision being made whereby the hinge may operate as a common form of hinge when opening and closing the window in the usual manner.

With the foregoing general object in view, the invention resides in certain novel features of construction and unique combinations of parts to be hereinafter fully described and claimed, the descriptive matter being supplemented by the accompanying drawings which form a part of this specification and in which:—

Figure 1 is an outer side elevation of a casement window showing the application of the invention;

Fig. 2 is a horizontal section on the plane of the line 2—2 of Fig. 1, with the window closed;

Fig. 3 is a horizontal section showing the sash swung open; and

Fig. 4 is yet another horizontal section illustrating the sash reversed for cleaning its outer side.

In the drawings above briefly described, the numeral 1 designates the frame of a casement window, whereas 2 has reference to the horizontally swinging sash thereof, these parts being of the usual or any preferred construction. The improved hinges 3 are employed at top and bottom and since the construction of both is the same, only one will be illustrated and described in detail.

A flat vertical hinge leaf 4 is secured by screws or the like 5 to the inner side of the frame 1 adjacent one edge of the sash 2, the outer edge of said leaf extending beyond the frame and being bent to form vertically

aligned hinge knuckles 6 which align with similar knuckles 7 carried by one end of an L-shaped horizontal arm 8 of flat formation, said arm having a long horizontal reach 60 and a short vertical reach contacting with the outer side of the sash as shown clearly in Fig. 2, said long reach extending along one horizontal rail of the sash and said short reach along one vertical rail. A vertical pin 65 9 is passed through the aligned knuckles 6 and 7, so that the arm 8 is hingedly mounted upon the plate 4 for horizontal turning. In most cases the arm 8 will be stamped to provide a stiffening rib 8':

The inner end of the arm 8 is bent to form vertically spaced hinged knuckles 10 alining with a central knuckle 10' on a second hinge leaf 11, said leaf 11 being secured by screws or the like 12 to the sash 2, substantially midway between the vertical edges of the latter. A pin 13 is passed through the knuckles 10 and 10' to hingedly connect the hinge leaf 11 with the arm 8, and in most cases this pin will be removable, but it is obvious that 80 it may well be in the form of a rivet if required. By providing a removable pin, however, the hinges may be more readily applied to the frame.

A turn button 14 is provided for holding 85 the arm 8 flat against the outer side of the sash 2, said button being in the form of a rigid lateral finger carried on the outer end of a short shaft 15 which passes through the hinged edge of the sash in the angle 90 between the short and long reaches of the arm 8, the inner end of said shaft being provided with a suitable handle 16 whereby it may be turned at will, and if occasion should demand, it will be obvious that suitable provision could well be made for locking said shaft against rotation. By locating the shaft 15 as shown, the finger 14 may operate over both the long and short reaches of arm 8 and will not therefore have to be 95 set in any particular position to become effective.

When the turn button 14 is in operative position as shown in Figs. 1, 2 and 3, the hinge will operate in the usual manner to 105 permit the opening of the sash as is illustrated more particularly in Fig. 3. When, however, the button 14 is released, the sash may be completely reversed upon the hinge at the inner end of the arm 8, as featured in 110 Fig. 4. It will thus be clear that the outer side of the window may be washed as easily

as the inner side, and after the washing operation, all parts may be restored to their initial positions and so held by the turn button 14, which may contact with either 5 the short or long reach of the arm 8.

I claim:

A window sash hinge comprising an L-shaped arm having a short vertical reach adapted to extend along one vertical rail of 10 the sash and a long horizontal reach to extend along one horizontal rail of said sash, a plate adapted to be secured to the horizontal rail of the sash and hinged on a vertical axis to the free end of said long reach, a 15 second plate adapted to be secured to the window frame and hinged to said short reach

along the outer edge of the latter, a horizontal shaft adapted to pass through the sash in the angle between said short and long reaches, a laterally extending rigid finger 20 on the outer end of said shaft adapted for contact with the outer surface of either reach of said arm to hold the latter against the sash, and a handle on the inner end of said shaft.

25

In testimony whereof I have hereunto set my hand in the presence of two subscribing witnesses.

ANDREW BYE.
